UNITED STATES PATENT OFFICE.

DANIEL DRAWBAUGH, OF EBERLYS MILL, PENNSYLVANIA.

BATTERY.

SPECIFICATION forming part of Letters Patent No. 733,949, dated July 21, 1903.

Application filed April 12, 1902. Serial No. 102,527. (No model.)

To all whom it may concern:

Be it known that I, DANIEL DRAWBAUGH, a citizen of the United States, residing at Eb-
erlys Mill, in the county of Cumberland and
5 State of Pennsylvania, have invented certain
new and useful Improvements in Batteries,
of which the following is a specification.

This invention relates to an improved dry
battery; and the main object of my invention
10 is the provision of a dry battery which is
composed of materials which lessen the cost
of manufacture of such batteries and which
increase the life and efficiency thereof. These
objects are attained by forming a dry battery,
15 as herein set forth and more particularly
pointed out in the claims.

In the accompanying drawings, Figure 1 is
a vertical central sectional view of a dry bat-
20 tery constructed according to and embodying
my invention. Fig. 2 is a top plan view
thereof; and Fig. 3 is a cross-section taken on
line *x x*, Fig. 1.

Referring by letter to the drawings, A des-
ignates an outer cylinder or package made of
25 zinc, this package having connected at one
point on its upper edge a binding-post B, to
which is made an electrical connection. Mounted in this cylinder in the center there-
of is the flat stick C, of carbon, which is pref-
erably made in a flat form and has connected
30 to its upper exterior end D the binding-post
E, to which is connected the other electrical
connection. Surrounding this carbon and con-
tained in the cylinder is a composition F, of
35 coke, plumbago, and a small quantity of
plaster-of-paris, enough to form a paste, so
that the carbon by means of its recesses G is
securely held in the cylinder. Around this
composition is placed a paper or other porous
40 material cylinder H, which forms a divisional
wall between the composition and the alkali
J, which is placed in the space between the
cylinder A and the cylinder H. This alkali is
generally made of a composition of concen-
45 trated lye or caustic soda, with a small amount
of plaster-of-paris to hold the composition in
form. I have also used hydraulic cement in
place of the plaster-of-paris and have found
it to be an excellent substitute.

50 Placed within the cylinder A, surrounding
the carbon and resting upon the parts F, H,
and J, is a ring K of heavy paper, upon which

is poured a layer L of melted pitch or tar to
hermetically seal the package, and thus pre-
vent the contents from becoming deteriorated 55
from exposure to the outside elements.

Both of the compositions F and J should be
thoroughly mixed before being placed in the
battery-form.

It is also evident that a battery constructed 60
according to this invention is much cheaper,
as the ingredients are cheaper, and that a
more practical and efficient battery is pro-
duced.

What I claim as new, and desire to secure 65
by Letters Patent, is—

1. A dry battery comprising an outer sur-
rounding electrode, a central opposite elec-
trode surrounded thereby, a composition of
carbon, plumbago, and a plastic material sur- 70
rounding the central electrode, and an alkali
composition incased by the first-mentioned
electrode and surrounding central electrode
and the first-mentioned composition.

2. A dry battery, comprising an outer sur- 75
rounding electrode, an excitant composition
of alkali and a plastic material, a centrally-
opposed electrode and a composition of car-
bon and plumbago surrounding said central
electrode.

3. A dry battery, comprising an outer sur- 80
rounding electrode, an excitant composition
of an alkali, a centrally-opposed electrode and
a composition of carbon and plumbago sur-
rounding the central electrode.

4. A dry battery, comprising an outer sur- 85
rounding electrode, an excitant composition
of an alkali and caustic potash, a centrally-
opposed electrode and a composition of car-
bon and plumbago surrounding said central 90
electrode.

5. A dry battery, comprising an outer sur-
rounding electrode, an excitant composition
of alkali and plaster-of-paris, a centrally-
opposed electrode and a composition of carbon 95
and plumbago surrounding said central elec-
trode.

6. A dry battery, comprising an outer sur-
rounding electrode, an excitant of caustic
potash and a plastic material, a centrally-
opposed electrode and a composition of carbon
and plumbago surrounding said central elec- 100
trode.

7. A dry battery, comprising an outer sur-

rounding electrode, an excitant composition of potash and plaster-of-paris, a centrally-opposed electrode and a composition of carbon and plumbago surrounding said central electrode.

8. A dry battery, comprising an outer surrounding metallic cylinder, a stick of carbon surrounded thereby, a composition of carbon and plumbago surrounding said stick, and an alkali surrounding the composition and the carbon stick and incased by the cylinder.

9. A dry battery, comprising an outer casting of zinc, an alkali excitant therein, a composition of coke, plumbago and a plastic material surrounded by the alkali, and an electrode mounted in the composition.

10. A dry battery, comprising an outer surrounding electrode, a porous cylinder mounted therein, an excitant made of an alkali and

a plastic material fitting in the space between the electrode and cylinder, a composition of coke, plumbago, and a plastic material fitting in said porous cylinder, and another electrode mounted in said composition.

11. A dry battery, comprising an outer casing of zinc, a cylinder of porous material mounted in said casing and providing a central containing-space and a peripheral containing-space, an excitant in the peripheral containing-space and a composition of carbon and plumbago and an electrode mounted in the central containing-space.

In testimony whereof I affix my signature in presence of two witnesses.

DANIEL DRAWBAUGH.
